Primary Examiner — Karen S Acker(74) *Attorney, Agent, or Firm* — Tutunjian & Bitetto, P.C.(57) **CLAIM**

The ornamental design for a display screen with graphical user interface, as shown and described.

DESCRIPTION

The FIGURE is a front view of the display screen with graphical user interface showing our new design;
 In the drawing, the outer perimeter of dot dash dot broken lines and the evenly spaced broken lines within this perimeter represent portions of the display screen with graphical user interface that form no part of the claimed design.
